C. A. PETERS

PLASTER BOARD

Filed Feb. 16, 1925

UNITED STATES PATENT OFFICE.

CHARLES A. PETERS, OF DOWNEY, CALIFORNIA, ASSIGNOR TO PETERS HOLDING COMPANY, A CORPORATION OF CALIFORNIA.

PLASTER BOARD.

Application filed February 16, 1925. Serial No. 9,608.

This invention particularly pertains to a composition wall board and to the method of manufacturing same.

An object of the invention is to provide a composition board which is adapted to be employed in forming surfaces of buildings and which is so formed as to provide a surface having the character of plaster to which may be applied either a plastic coating or the fluid coatings commonly employed in the finishing and decoration of plastered walls.

Another object is to provide an effective method for manufacturing a wall board of the above character.

The type of wall board to which the present invention pertains embodies a panel or slab formed of a suitable composition which, during the course of manufacture of the board, is of plastic character, and which composition preferably includes gypsum or similar cementitious material intermixed with a suitable fibrous filler preferably consisting solely of asbestos fibers, but which may be formed of any other fibers that will serve as a binder and reinforcement of the mass, these ingredients being admixed with water to form a plaster which hardens when dry.

The plaster panel is surfaced on one side with a backing sheet which may comprise paper, as commonly employed in wall board construction, or may consist of a woven fabric, and the other or outer face of the panel is formed with a fibrous foraminous or reticulated reinforcing sheet preferably consisting of cotton gauze of open mesh.

In carrying out the present invention, the foraminous sheet is applied to the surface of the plaster, preferably in such manner that the outer surface of the board will be so formed as to provide a comparatively hard and compact shell over the foraminous sheet surface to which may be applied any suitable finish coating.

A particular object of the invention is to provide means and for readily forming the roughened hard shell surface of the board.

The mode of carrying out the foregoing objects, as well as such objects, features and advantages of the invention as may subsequently appear is hereinafter described and is illustrated by way of example in the accompanying drawings in which the several

views depict constructions and arrangement of elements and parts whereby the invention may be carried into effect.

Referring to the drawings the several views are as follows:—

Figure 1 is a diagram illustrating the manner of forming the board;

Figures 2, 3, 4, 5 and 6 are details illustrating more clearly the mode of forming the board;

Figure 7 is a detail in plan of a fragmentary portion of the board showing the roughened outer surface of the board; and

Figure 8 is a view in section of the finished board as seen on the line 8—8 of Figure 7.

More specifically, 10 indicates a long horizontally extending endless conveyor belt which passes around direction rollers 11 and 12 and is adapted to be advanced by any suitable driving mechanism as is common in wall board manufacture.

A fibrous backing strip 13 of paper or similar material is fed from a roll 14 over a table 15 and between a pair of forming rollers 16 and 16', and is directed onto the upper lead of the belt 10. A suitable plastic composition 17 in a wet unstable condition, preferably formed of gypsum, asbestos fiber and water, is deposited on the strip 13 and is spread thereover as the strip advances over the table 15 and passes between the forming rollers. A facing and reinforcing strip 18 of fibrous foraminous material, such as cotton gauze or netting of open mesh and of a width corresponding to that of the backing strip is fed from a roll 19 around and under the upper forming roller 16 and is impressed by the latter onto the plastic body as it passes between the forming rollers together with the backing strip 13. The forming rollers are spaced apart and operate to form the advancing strip 13, plastic body 17 and foraminous strip 18 into a homogeneous panel of predetermined thickness, which passes onto the upper lead of the belt 10 and is carried forward by the latter. The upper strip 18 being foraminous a portion of the plastic composition will be squeezed therethrough as it passes between the forming rollers, and accordingly, portions of the composition will adhere to the periphery of the upper roller 16. The wet plastic thus adhering to the roller 16 is scraped off and caused to fall back upon the upper surface

of the advancing panel. The panel is then passed successively between a series of pairs of spaced rollers as indicated at A, B, C and D, and is thereby subjected to a rolling and 5 pressing action. The pairs of rollers A, B, C, and D are spaced such distance apart and the belt 10 is moved at such speed that the plastic composition of the panel will still be wet and unstable as it passes between the 10 end pair of rollers D, although in some instances the end rollers D may be spaced such distance from the pair of rollers C that the plastic will be partly set on passing therebetween. The pair of rollers A are 15 spaced apart a distance slightly less than the spacing of the forming rollers 16—16'; the pair of rollers B are spaced apart a distance slightly less than the spacing of the rollers A; and the pair of rollers C are 20 spaced apart a distance slightly less than the spacing of the rollers B so that as the panel advances through the series of pairs of compressing rollers A, B and C, it is subjected to a series of successive impressing 25 and rolling actions whereby the solids of the plastic composition are pressed into a more and more compact body. This compressing action of the rollers A, B and C serves to force the more fluid portion of the plastic to 30 the surface of the plastic body and thus coats the latter with a rich liquid mixture of gypsum and water which thickens as the panel advances between the successive pair of rollers. Portions of the liquid will 35 adhere to the peripheries of the upper rollers of the pairs of rollers A, B and C and is scraped off these rollers and caused to drip back onto the surface of the panel as shown in Figures 3, 4 and 5 so that when the panel 40 passes from between the rollers C the top surface of the panel will be formed with a series of closely arranged longitudinal extending irregular ribs or ridges 20, as shown in Figures 7 and 8 which ridges will 45 project above the foraminous sheet and will impart a roughened surface to the panel. The final pair of rollers D are employed to flatten the apexes of such ridges 20 as may 50 project excessively from the surface of the panel, if so desired; they being spaced apart a distance slightly exceeding that of the rollers C where it is desired to flatten the ridges and render them broad, and being spaced further apart when it is desired to 55 merely flatten the excessively high points or portions of the ridges. Where it is desired to form the board with an exceedingly rough surface the rollers D may be dispensed with or the upper roller of the pair 60 positioned so that it will not contact the ridges. Such portion of the plastic as may cling to the uppermost roller of the pair of rollers D is removed therefrom by a scraper as indicated at 21 and may be inhibited from 65 falling back on the surface of the panel if

so desired, it being collected in a trough formed by the scraper 21 and removed therefrom from time to time as occasion requires.

The strip of board thus formed is carried forward on the conveyor belt for such distance and for such length of time that the plastic material will set whereupon the strip is trimmed and cut into lengths in any desired manner to form panels of any desired dimensions which are subsequently kiln 75 dried whereupon they are in readiness to be employed in forming a wall surface. In use the panels are nailed or otherwise secured to a suitable backing or support with the roughened surface outermost, which surface will have the appearance and character of a plastered wall and may then be finished and decorated in any manner applicable to the treatment of plastered walls, and if desired may be coated with plaster. 80 85

By forming the board in the manner set forth the foraminous strip will serve as a screen when the wet unstable plastic composition is passed between the several pairs of rollers, to prevent the coarse fibrous constituents of the plastic composition from adhering to the compressing rollers and yet permit a portion of the fluid constituent of the plastic composition to pass through the strip 18 and submerge the latter which fluid by reason of being worked by the rollers will be rendered rich so that when it sets a hard dense shell will be formed on the surface of the board in which the strip will be imbedded. However, the extent of submersion of 90 the foraminous strip 18 in the plastic liquid may be varied as occasion may require, which is accomplished by regulating the fluidity of the plastic composition and by adjusting the spacing of the compressing rollers. A 95 very desirable surface is obtained by so submerging the foraminous strip in the main body of the plastic that the weave of the strip will appear in the depressions formed between the raised ridges 20 as shown in 100 Figure 7. 105

In practice, to form the finished board of a thickness of about three-eighths of an inch the forming rollers 16—16' are spaced apart about seven-sixteenths of an inch, and the 115 pairs of rollers A, B and C are spaced respectively thirteen-thirty seconds, three-eighths and eleven-thirty seconds inches apart, while the end rollers D are spaced about three-eighths of an inch apart. 120

In the preferred embodiment of the invention a thread-like fibrous material such as asbestos fibers is incorporated in the plastic composition so that the ends of some of the fibers will be caused to project into the interstices formed by the mesh of the foraminous strip 18 on pressing the strip onto the plastic, as described, so that the bond between the plastic and the strip will be increased. 125 130

5 By working the wet plastic body in the manner set forth the portion of the plaster carrying the fibrous filler and which extends between the backing sheet and the foraminous sheet will be comparatively soft when dry while the outer portion thereof will be formed with a hard shell as before stated.

10 While I have shown and described the use of three sets of compressing rollers A, B and C, it is to be understood that satisfactory results may be obtained by employing either a lesser or greater number of such rollers, and that while I have shown and described a specific embodiment of the invention 15 I do not limit myself thereto but reserve the right to all such variations and modifications as properly fall within the scope of my invention and the terms of the following claims.

20 I claim:—

1. A wall board comprising a plaster panel including a relatively soft body formed with a hard surface, and a sheet of netting embedded in the hard surface portion of the panel through the interstices of which project and over the mesh of which netting extends portions of the plaster; the hard surface of the plaster being formed throughout with ridges.

30 2. A plaster board having a fibrous netting on the surface thereof through which project bodies of plaster forming the surface of the board throughout the entire area thereof with ridges.

35 3. A wall board comprising a plaster panel, a backing sheet surfacing one side of said panel, and a sheet netting on the other side of said panel through which project irregular bodies of plaster forming the board throughout the area of one side thereof with a roughened surface of plaster.

40 4. A wall board comprising a panel formed of plaster having the back portion of its thickness formed relatively soft and provided with a hard shell front surface, a fibrous netting on the front surface through which project irregular bodies of the plaster whereby the front surface of the board is formed throughout the area thereof with a roughened surface of hard plaster, and a backing sheet surfacing the back portion of said panel.

50 5. The method of forming a plaster board

55 consisting in coating a backing sheet with a wet unstable plastic composition, embedding a sheet of netting in the surface of the plastic body under pressure, subjecting the surface of the plastic body to a rolling and pressing action while wet so as to squeeze the more liquid content of the plastic composition through the interstices of the sheet, the front surface of the board being formed throughout the area thereof with a roughened surface of plaster, and then allowing the plastic to set and dry.

60 6. The method of forming a plaster board consisting in coating a backing sheet with a wet unstable plastic composition, embedding a foraminous sheet in the surface of the plastic body under pressure, subjecting the 70 surface of the plastic body to a rolling and pressing action while wet so as to cause a thin portion of the plastic to rise through the interstices of the sheet, removing portions of the thin plastic and causing such 75 portions to drip back on the surface of the plastic body so as to form ridges thereon, and then allowing the plastic to set and dry.

7. The method of forming a plaster board 80 consisting in coating a backing sheet with a wet unstable plastic composition, embedding a foraminous sheet in the surface of the plastic body under pressure, subjecting the surface of the plastic body to a rolling and pressing action while wet so as to cause a 85 thin portion of the plastic to rise through the interstices of the sheet, removing portions of the thin plastic and causing such 90 portions to drip back on the surface of the plastic body so as to form ridges thereon, subjecting the ridges to a flattening action, and then allowing the plastic to set and dry.

8. The method of forming a plaster board 95 consisting in coating a backing sheet with a wet unstable plastic material including in its composition gypsum, fibrous substance and water; placing a foraminous sheet on the surface of the plastic body, subjecting the plastic body while soft and wet to a series of successive impressing and rolling actions to bring a rich fluid mixture of the gypsum and water to the surface thereof through the foraminous sheet, and allowing the plastic to set and dry.
